UNITED STATES PATENT OFFICE

168,467

PORTABLE POWER-OPERATED SAW

Eugene J. Majewski, Chicago, Ill., assignor to Portable Electric Tools, Inc., Chicago, Ill., a corporation of Illinois

Application June 30, 1952, Serial No. 20,415

Term of patent 14 years

(Cl. D93—3)

To all whom it may concern:

Be it known that I, Eugene J. Majewski, a citizen of the United States, residing at Chicago, in the county of Cook and State of Illinois, have invented a new, original, and ornamental Design for a Portable Power Operated Saw, of which the following is a specification, reference being made to the accompanying drawings forming a part hereof.

In the drawings:

Fig. 1 is a front perspective view of a portable power operated saw showing my new design;

Fig. 2 is a left-hand end view thereof;

Fig. 3 is a plan view;

Fig. 4 is a rear view shown tilted to a 45 degree angle;

Fig. 5 is a front view thereof; and

Fig. 6 is a detailed end view of the motor taken from the right of Fig. 3.

The dominant feature of my design is that shown in full lines.

I claim:

The ornamental design for a portable power operated saw, substantially as shown and described.

EUGENE J. MAJEWSKI.
